Primary Examiner — Gino Colan*Assistant Examiner* — Gregory G McLemore(74) Attorney, Agent, or Firm — Connie R. Masters(57) CLAIM

The ornamental design for a set of playing cards, as shown and described.

DESCRIPTION

FIG. 1 is a front view of a set of playing cards, showing my new design;

FIG. 2 is a back view of each card thereof;

FIG. 3 is a top view of each card thereof the bottom view of each card thereof being a mirror image of the top view; and, FIG. 4 is a right side view of each card thereof the left side view of each card thereof being a mirror image of the right side view.

The broken lines in the figures depict portions of the set of playing cards that form no part of the claimed design. The dot-dash-dot broken lines in the figures define the bounds of the claimed design and form no part thereof.

1 Claim, 2 Drawing Sheets(56)
